4 Claims. (Cl. 252—153)

(Granted under Title 35, U.S. Code (1952), sec. 266)

The invention described herein may be manufactured and used by or for the Government for governmental purposes without the payment to us of any royalties thereon.

This invention relates to the removal of carbon deposits from parts of internal combustion engines. More particularly the invention relates to a carbon-loosening solvent suitable for use in softening and facilitating the effective removal of carbon, gum, oil, tar and other surface contaminants, except rust and corrosion, from items such as pistons, piston rings, carburetors, fuel pumps, and engine assemblies.

Various degrees of difficulty exist in the removal of so-called carbon deposits, depending on the particular conditions of operation of the engine, the nature of the lubricating oils, the nature of the fuel, and the type of metal used in the manufacture of pistons. Variations in the resistance to removal of such carbon deposits are as wide as the variations in the types of contaminants formed on the engine parts. For example, so-called light carbon deposits are readily removed where the chief active component of the carbon-loosening solvent is cresylic acid. Other types of carbon deposits are more difficult to remove, however, and require cleaning compositions which contain both cresylic acid and chlorinated solvents. Cresylic acid type compounds, however, are undesirable because of their toxicity, difficulty of disposal, and their limited supply which might well become critical at times of national emergency. Chlorinated compounds are also undesirable because of their toxic hazards. As a general rule, the smaller the molecule of the cleaning compound the faster its speed of cleaning. For example, methylene chloride has been found to be one of the most effective cleaning compositions when used as one of the principal active components of carbon-loosening solvents. Methylen chloride has the relatively high M.A.C. value of 500 p.p.m., that is, for safety purposes, the maximum allowable concentration of methylene chloride vapor in the air is approximately 500 parts per million. Where concentrations of methylene chloride exceed that figure, a definite toxic hazard is presented. Since engine parts to be cleaned are either dipped directly into containers of solvent or the solvent is brushed on the parts and allowed to stand for several hours before removal, the concentration of solvent in the air merits serious consideration. In spite of its relatively high M.A.C. value, however, methylene chloride is undesirable for use as a carbon-loosening solvent since it has a low boiling point of 104° F. and its M.A.C. value is far exceeded at many ambient temperatures. For example, at 72° F. the concentration of methylene in the surrounding air would be in the neighborhood of 500,000 p.p.m. For purposes of this invention, a non-toxic cleaner is defined as one which is usable at temperatures at which each of the ingredients has a vapor concentration below the M.A.C. value for that ingredient.

Accordingly, the primary object of this invention is the formulation of a cleaner having a cleaning ability equal to that of cleaners containing a combination of chlorinated hydrocarbons and cresylic type compounds but in

2

which chlorinated hydrocarbons of the naphthenic, aliphatic or aromatic types, as well as cresols, phenols, and their related compounds or their salts are absent.

A second object of this invention is the formulation of a carbon-loosening solvent having a desired degree of cleaning ability, but in which the vapor concentrations of hazardous components are kept below their maximum allowable concentration values at the temperature of use.

The further object of this invention is the provision of compositions for removing carbon deposits which will remain stable and effective over a wide range of conditions.

Pursuant to the above mentioned objects of this invention, we have found that mixtures of monoethanol amine, water, and ethylene glycol mono-butyl ether provide the desired degree of cleaning ability even in the absence of chlorinated hydrocarbons and phenolic or cresylic type compounds. When this base is used, it has been found possible to adjust the composition in such a manner that the vapor pressures of all components lie below their M.A.C. (maximum allowable concentration) values even at temperatures as high as 130° F. At a temperature of 130° F. the desired degree of cleaning is generally obtained in approximately four hours or less, which is considered adequate for all practical purposes.

It has also been found that additional improvement in cleaning may be obtained by the addition of small amounts of propylene glycol (0.5—1.2% by volume of total cleaner) or ethylene glycol (0.3—0.8% by volume of cleaner) and by substituting ethylene glycol monoethyl ether in all or part for the corresponding butyl ether, mol. for mol. The upper concentration of this ethyl ether, however, must be limited if its vapor concentration is to be maintained below its M.A.C. value at 130° F. In removing carbon deposits from engine parts, brushing with a bristle brush is usually required subsequent to soaking in the cleaner composition. Brushing is sometimes difficult, however, if no soap or detergent is present. Accordingly, it is advantageous to include some soap or detergent in these cleaner compositions.

It has also been found that the same degree of cleaning may be obtained by substituting, in part, aromatic hydrocarbons or mixtures of such hydrocarbons for the ethylene glycol mono-butyl ether. Typical characteristics of aromatics which have properties lying in the proper range of cleaning and which have vapor pressure characteristics enabling them to be properly utilized for the purposes of the low toxicity cleaner of this invention are:

50	Aromatic content	percent minimum	88
50	Flash point	° F minimum	140
50	Initial boiling point ¹	do	350
50	50% distillation point ¹	° F maximum	390
50	End point ¹	do	435

¹ ASTM Method D86-52.

Other aromatic hydrocarbons may be used in cases where vapor concentrations are not a factor. In order to prevent gelation which may occur on evaporation of volatile solvents, it may be desirable in some cases to add small amounts of a gelation inhibitor or phase stabilizer. In this respect either 3 methoxy butanol or hexylene glycol in concentrations of from 1 to 5 percent by volume of the total cleaner has been found to be effective. Additionally it is frequently advisable to add a corrosion inhibitor to the cleaner of this invention, particularly where metals such as zinc, copper, brass, lead, or aluminum are being cleaned. Sodium silicate has been found to serve effectively as a corrosion inhibitor. Only small amounts of sodium silicate have been found to be necessary to prevent corrosion. Excess silicate settles to the bottom of the mixture and the clear supernatant liquid may be used directly, or it may be filtered by means of

any of the usual filter media such as paper mat and the like.

Although monoethanol amine is used in the preferred modification of this invention, other types of primary hydroxyamines may be used in its place. A primary hydroxyamine is essential, however, to obtain proper cleaning. Other types of amines, for example, diethanol amine, diethylethanol amine or triethanol amine have yielded poor results.

The low vapor pressure of the hydroxyamines is believed due to the association of the hydroxy group of one molecule with the amine group of another, through hydrogen bonding. This associated molecule apparently breaks down readily to give the reactions characteristic of an amine. The efficiency of monoethanol amine in conjunction with the water and the ethylene glycol monobutyl ether (alone or in part substituted by aromatic hydrocarbons) may be due to the independent action of the various cleaner components on the components of the carbon deposits, with various degrees of lipophilic and hydrophilic character. Too much of one component results in too little, relatively, of the others, so that "carbon" components are not removed which would otherwise expose it to soluble "carbon" components. Also, different particles of even the same soil molecule, micelle, or larger particle may successively become solvated with the proper solvent. Insufficient quantities could result in the displacement of equilibria so that desolvation is favored before complete dispersion of the molecule, micelle, or larger particle can occur.

The following specific examples are given by way of illustrating the practice of this invention. It should be understood, however, that monopropanol amine may be substituted mol. for mol. for the monoethanol amine in all the illustrations given below. Also, propylene glycol monobutyl, or monoethyl or mono-isopropyl ether, ethylene glycol mono-propyl or isopropyl ether and ethylene glycol mono-phenyl ether may be substituted mol. for mol. for the ethylene glycol monobutyl ether given in the below illustrations. Molecular volumes in milliliters may be obtained for these substitutes by dividing the densities of

of this invention are: Soap 0 to 23%; aromatic hydrocarbons 0 to 65%; ethylene glycol mono-butyl ether 7 to 64%; mono ethanol amine 2 to 27%; water 3.5 to 57%; 3 methoxybutyl alcohol 1 to 3%; propylene glycol 0.5 to 1.2%; ethylene glycol 0.3 to 0.8%. In mols per liter, ethylene glycol mono-butyl ether varies from .534 to 4.90 and mono ethanol amine varies from .335 to 4.52.

While the instant invention has been shown and described herein in what is conceived to be the most practical and preferred embodiment, it is recognized that departures may be made therefrom within the scope of the invention, which is therefore not to be limited to the details disclosed herein but is to be accorded the full scope of the claims so as to embrace any and all equivalents.

What is claimed and desired to be secured by United States Letters Patent is:

We claim:

1. A non-toxic, carbon-loosening composition consisting essentially, by volume, of from 2 to 27 percent of a primary hydroxyamine selected from the group consisting of monoethanolamine and monopropanolamine, of from 7 to 64 percent of an ether selected from the group consisting of ethylene glycol monobutyl ether, ethylene glycol monoethyl ether, propylene glycol monobutyl ether, ethylene glycol monopropyl ether and ethylene monophenyl ether, of from 3.5 to 57 percent water and of from 0.3 to 1.2 percent of a polyhydric alcohol selected from the group consisting of ethylene glycol and propylene glycol.
2. A composition as set forth in claim 1 containing from 1 to 5 percent by volume of a phase stabilizer selected from the group consisting of methoxy butanol and hexylene glycol.
3. A composition as set forth in claim 1 containing a sodium silicate corrosion inhibitor.
4. A non-toxic, carbon-loosening composition consisting essentially, by volume, of from 2 to 27 percent monoethanolamine, of from 7 to 64 percent ethylene glycol monobutyl ether, of from 3.5 to 57 percent water, of from 0.5 to 1.2 percent propylene glycol, and of from 1 to 5 percent methoxy butanol.

Example No.	1	2	3	4	5	6	7	8	9	10	11	12	13	14	15	16	17
Soap	16	16	16	16	16	16	15.8	23	10.5								
Aromatics	45.6	45.3	8.5	41.4	64.8		13.1	34.1	39.6								
Ethylene Glycol Mono-Butyl Ether	30.4	30.2	10.5	27.6	7.2	64	23	13.8	21.9	25.4	19.4	11.9	12.0	9.5	0.6	12.6	12.9
Mono-Ethanol Amine	5	5	25	2	5	7	22	19.1	4.2	4.9	21.5	21.0	21.2	21.0	21.2	22.3	22.8
Water	3	3.5	40	13	7	13	55	24.38	16.8	19.6	53.7	52.0	52.5	52.0	52.5	55.1	56.4
Propylene Glycol							.76				1.1	1.1			1.1		
3-Methoxy-Butyl Alcohol							1.47			2.1							
Sodium Silicate, 40°							.12			0.1	0.3	0.5	0.3	0.5	0.5	0.3	
Ethylene Glycol Mono-Ethyl Ether							1.47			2.1							
Ethylene Glycol Mono-Phenyl Ether											7.0	7.1	9.4	9.5	7.4	7.6	
Hexylene Glycol											4.8	4.8	4.8	4.8			
Synthetic Detergent											1.9	1.9	1.9	1.9	2.1		

these substances into their molecular weights. All volumes are measured between 65° F. and 100° F. and all values are in percent by volume unless otherwise specifically designated.

The compositions given in above Examples 3, 7, 8 and 11-13 represent preferred embodiments of the invention in view of the fact they possess the low M.A.C. values desired in this type of composition.

In compositions using soap, where aromatic hydrocarbons are used, it is desirable that the percentage of soap be between 10 and 23 percent. In the absence of aromatic hydrocarbons, approximately 2 to 23 parts per volume of soap or synthetic detergents are added to compositions. Such additions much improve the ease of brushing.

The ranges of percent by volume in which the components may be used if incorporated in the cleaning composition and which are considered to be within the scope
